A. E. OLSEN

WINDOW OPERATING DEVICE

Filed Aug. 15, 1922

Inventor

Anton E. Olsen

By his Attorney

Edgar Date & Co

UNITED STATES PATENT OFFICE.

ANTON E. OLSEN, OF NEW YORK, N. Y., ASSIGNOR OF ONE-HALF TO GEORGE M. REICHENBACH, OF NEW YORK, N. Y.

WINDOW-OPERATING DEVICE.

Application filed August 15, 1922. Serial No. 581,948.

To all whom it may concern:

Be it known that I, ANTON E. OLSEN, a citizen of the United States, and residing at New York, in the county of New York and State of New York, have invented certain new and useful Improvements in Window-Operating Devices, of which the following is a specification, such as will enable those skilled in the art to which it appertains to

10 make and use the same.

This invention relates to window operating devices and particularly to devices of this class designed for use in connection with the body framework of motor vehicles 15 and more particularly for operating comparatively wide but low window panels in such framework, and the object of the invention is to provide a device of the class and for the purpose specified provided with 20 two laterally directed pivoted levers adapted to cooperate with and raise and lower the window panel with means for actuating said levers; a further object being to provide means for balancing the window panel 25 to facilitate the raising and lowering thereof by an aperture; and with these and other objects in view the invention consists in a device of the class and for the purpose specified, which is simple in construction, 30 efficient in use, and which is constructed as hereinafter described and claimed.

The invention described and claimed herein is an improvement on that shown and described in a co-pending application, filed 35 January 30, 1922, Ser. No. 582,603, and is fully disclosed in the following specification, of which the accompanying drawing forms a part, in which the separate parts of my improvement are designated by suitable reference characters in each of the views, and 40 in which:—

Fig. 1 is a view showing a part of the framework of a motor vehicle body, showing one of my improved window operating devices mounted therein.

Fig. 2 is a partial section on the line 2—2 of Fig. 1.

Fig. 3 is a partial section on the line 3—3 of Fig. 1, and

50 Fig. 4 is a partial section on the line 4—4 of Fig. 2.

In the drawing I have shown at 5 a part of the framework of the body of a motor vehicle, in which a window panel 6 is mov- 55 ably mounted, said panel being provided at

its lower edge with a metallic strip 7 carrying two tracks or runways 8, in which roller bearings 9 are movably mounted. The bearings 9 are mounted in connection with the free ends of levers 10, pivoted to an attaching plate 11 as shown at 12 and provided at their inner ends with elongated apertures 13, in which pins 14 carried by a block 15 are adapted to operate.

The block 15 is internally threaded to receive a screw shaft 16, one end of which is fixed to the plate 11 as shown at 17, and the other end of which extends into a yoke 18 mounted on a pin or bolt 19 secured to the plate 11. Mounted on the pin or bolt 19 60 is a bevel gear 20 which meshes with a pinion 21 on the screw shaft 16, and the gear 20 is provided with an angular extension 22 on which a crank 23 is mounted.

The gear 20 and pinion 21 are enclosed in 65 a cup-shaped jacket 24 which is secured to the plate 11. Two rods 25 are pivoted to the levers 10 and passed through keepers 26 on the plate 11, and compression springs 27 are mounted on said rods and other springs 28 are secured to the plate 11 and to the levers 10, and all of said springs operate to balance 70 the window panel 6 in the operation thereof.

The operation of my improved window operating device will be readily understood 75 from the foregoing description when taken in connection with the accompanying drawing and following statement. In the position of the parts shown in Fig. 1 of the drawing, the window panel is in a half open 80 position and in the operation of fully opening said window the crank 23 is rotated in the proper direction which will cause the block 15 to move upwardly and the levers 10 to swing downwardly into the position indicated in dotted lines, in which operation the roller bearings 9 slide inwardly in the tracks or runways 8. It will also be understood 85 that if the window panel 6 be moved into a closed position, the block 15 will move 90 downwardly and the levers 10 upwardly, and the springs 27 and 28 operate in both instances to counter-balance the weight of 95 the window panel.

It will also be understood that my improved window operating device is of unitary construction, in other words, all of the operative parts are mounted in connection 100 with the attaching plate 11 and while I have shown certain details of construction 105 110

for carrying my invention into effect, it will be apparent that I am not necessarily limited to these details and various changes therein and modifications thereof may be made within the scope of the appended claims without departing from the spirit of my invention, or sacrificing its advantages.

Having fully described my invention, what I claim as new and desire to secure by Letters Patent, is:—

1. A window operating device of the class described, comprising a screw shaft, means for rotating said shaft, a block in threaded engagement with said shaft and adapted to be moved longitudinally thereof in the rotation of said shaft, oppositely disposed levers pivoted independently to stationary supports, one end of said levers being in operative connection with said block, and the other end of said levers being provided with antifrictional devices.

2. A window operating device of the class described, comprising a screw shaft, means for rotating said shaft, a block in threaded engagement with said shaft and adapted to be moved longitudinally thereof in the rotation of said shaft, oppositely disposed levers pivoted independently to stationary supports, one end of said levers being in operative connection with said block, and the other end of said levers being provided with antifrictional devices, compression springs in operative connection with the first named ends of said levers, and other tensional devices in operative connection with the other end portions of said levers.

3. The combination with a window panel provided at its lower edge with tracks or runways of a window panel operating device comprising levers one of the ends of which is in operative connection with said tracks or runways, said levers being pivoted adjacent the other end portions thereof, a member in operative connection with the last named ends of said levers beyond the pivots thereof, a screw shaft in threaded engagement with said member and by means of which said member may be operated to actuate said levers and raise and lower said window panel, and means for rotating said screw shaft.

4. The combination with a window panel provided at its lower edge with tracks or runways of a window panel operating device comprising levers one of the ends of which is in operative connection with said tracks or runways, said levers being pivoted adjacent the other end portions thereof, a member in operative connection with the last named ends of said levers beyond the pivots thereof, a screw shaft in threaded engagement with said member and by means of which said member may be operated to

actuate said levers and raise and lower said window panel, means for rotating said screw shaft, said means comprising suitable gears, and a crank for rotating said gears.

5. The combination with a window panel provided at its lower edge with tracks or runways of a window panel operating device comprising levers one of the ends of which is in operative connection with said tracks or runways, said levers being pivoted adjacent the other end portions thereof, a member in operative connection with the last named ends of said levers beyond the pivots thereof, a screw shaft in threaded engagement with said member and by means of which said member may be operated to actuate said levers and raise and lower said window panel, means for rotating said screw shaft, said means comprising suitable gears, a crank for rotating said gears, and means connected with said levers for counterbalancing said window panel in the operation thereof.

6. A window operating device of the class described comprising a screw shaft, a member in threaded engagement with said shaft and movable longitudinally thereof, said member being provided with oppositely disposed extensions, oppositely disposed levers, one of the ends of which is mounted in connection with the extensions of said member whereby the movement of said member will actuate said levers, the other end portions of said levers being in operative connection with the window to be operated, said levers having fixed pivots adjacent and outwardly of the coupling of said member therewith, and means for rotating said shaft.

7. A window operating device of the class described comprising a screw shaft, a member in threaded engagement with said shaft and movable longitudinally thereof, said member being provided with oppositely disposed extensions, oppositely disposed levers, one of the ends of which is mounted in connection with the extensions of said member whereby the movement of said member will actuate said levers, the other end portions of said levers being in operative connection with the window to be operated, said levers having fixed pivots adjacent and outwardly of the coupling of said member therewith, means for rotating said shaft, compression springs cooperating with the first named end portions of said levers, and other springs cooperating with the other end portions of said levers adjacent the pivotal mountings thereof.

In testimony that I claim the foregoing as my invention I have signed my name this 10th day of August, 1922.

ANTON E. OLSEN.
